(57) **CLAIM**

The ornamental design for the garden lamp with pumpkin
shaped lantern, as shown and described.

DESCRIPTION

FIG. 1 is a side perspective view of the garden lamp with
pumpkin shaped lantern in accordance with my design;
FIG. 2 is a left side elevational view of the garden lamp with
pumpkin shaped lantern in accordance with my design, the
right side being substantially identical thereto;
FIG. 3 is a front side elevational view of the garden lamp
with pumpkin shaped lantern in accordance with my design,
the rear being substantially identical thereto;

FIG. 4 is a top plan view of the garden lamp with pumpkin
shaped lantern in accordance with my design; and,

FIG. 5 is a bottom plan view of the garden lamp with
pumpkin shaped lantern in accordance with my design.

The broken lines show the solar batteries and a photoresistor
and are not considered part of the design claimed.
